UNITED STATES PATENT OFFICE.

WILLIAM F. FOLMER, OF ROCHESTER, NEW YORK, ASSIGNOR TO EASTMAN KODAK COMPANY, OF ROCHESTER, NEW YORK, A CORPORATION OF NEW YORK.

CUT-FILM HOLDER.

Application filed March 17, 1926. Serial No. 95,267.

This invention relates to photography, and more particularly to holders in which sheets of photographically light sensitive material upon suitable supports may be exposed in a camera. One object of my invention is to provide a holder in which the photographic material holders are held accurately in position. Another object is to provide a suitable light locking means between the two holders which are placed back to back in the carrying frame. Another object is to provide holders which are supported on all four sides, and other objects will appear from the following specification, the novel features being pointed out in the claims at the end thereof.

This application is a continuation in part of my copending application for cut film holders, Serial No. 654,489, filed July 28, 20 1923.

In the drawings, wherein like reference characters denote like parts throughout:

Fig. 1 is a plan view of a holder constructed in accordance with and embodying 25 one form of my invention;

Fig. 2 is an enlarged detail section on line 2—2 of Fig. 1;

Fig. 3 is an enlarged section on line 3—3 of Fig. 1;

Fig. 4 is an enlarged detail section on line 4—4 of Fig. 1;

Fig. 5 is a perspective view of a preferred type of sheath removed from the holder; and

Fig. 6 is an enlarged detail section of another embodiment of my invention, this section being taken across one of the side rails of a holder.

I have selected for illustrating a preferred 40 embodiment of my holder, a double holder since this is the type generally used by photographers in this country. Certain features of the invention are equally useful when applied to a single holder.

In photographic cut film holders, particularly in the larger sizes, such as the 8 x 10, 10 x 12, 7 x 17, 12 x 20, etc., it has been difficult to construct a holder which would be perfectly light tight and remain so. It 50 has also been difficult to make a large size holder in which a sheet of cut film could be made to lie accurately in a plane surface.

Coming now to the drawings, as shown in Fig. 1, the holder designated broadly as 1,

consists of a frame having a cross bar 2 at 55 the top, light guard plates 3 extending across the top and spaced from the cross bar 2, side bars 4 and a bottom 5' to which is hinged by fabric 6 the doors 5. This door construction is well known, being shown in U. S. 60 Patent No. 603,972, Schaub, May 10, 1898. Dark slides 7 are provided with the usual handles 8 which may be engaged by latches 9 which are carried by the top bar 2.

As will be noted from Fig. 2, the cross bar 2 is provided with depressions 12 into which the spring light guard plates 22 are adapted to lie. When the dark slide 7 is in place, the spring plate presses against the dark slide. When the slide is removed, as 70 shown in the left hand side of this figure, the light guard plate enters the groove 12 so that light is prevented from entering through the slot 31 which receives the dark slide 7.

The sheets of cut film F are held in position in this holder by means of sheaths 15. These sheaths may consist of a metal plate having longitudinal overhanging flanges 38 and an end overhanging flange 39, and an 80 unflanged end 40. The sheath of Fig. 5 differs from that used in the embodiment shown in Figs. 1 to 4 inclusive in that the flanges 38 are formed above a base plate bent at 138 so as to raise the edges of the 85 sheet film. This structure is particularly useful in holding large sheets of cut film flat and it is disclosed in U. S. Patent No. 1,139,079, Sievers, May 11, 1915.

In the embodiment shown in the first four figures of the drawings, the film sheaths 15 are supported in the holder in the following manner: There are grooves 28 cut into cross bar 2 adapted to receive the flanges 39 of the two sheaths. These grooves are spaced 95 by a tongue 37. The side rails 4 of the holder are provided with a relatively wide groove 49 which receives the side flanges 38 which, in this embodiment, are spaced by a central plate 17. This plate is preferably 100 made of some material which will not readily warp, such as pressboard. As shown in Fig. 4, the bottom rail 5' of the holder is provided with a tongue 45 which is of the same width as plate 17. The unflanged 105 ends 40 of the sheaths are spaced by this tongue.

The films are loaded into the sheaths by

swinging open the doors 5' and sliding the films under the ends 50 of the flange 38. As will be noted from Fig. 2, the edge 39' of flange 39 is bent outwardly so as to direct 5 a film being slid into the sheath under this flange. It will be noted from this construction that the film sheaths 15 may be manufactured separately and after having been made perfectly flat may be built into the 10 frame, above described, so as to be held rigidly in position in the grooves. As will be noted from Fig. 2, the grooves 28 in the cross bar 2 are of somewhat greater depth than necessary so that this permits the 15 sheaths to move if the frame should warp. I also prefer to have at least one of the grooves 49 in the side rails 4 slightly deeper than necessary so that the frame may expand or contact to a limited degree without caus- 20 ing the metal sheaths to be bent or warped out of shape. An important feature in this construction is that the sheaths, by entering the groove in the side and top members of the frame, form a light-tight joint therewith 25 so that the exposure of one film will not admit light around the edges of the holders to the film on the other side. The bottoms 40 of the sheaths are also perfectly light-tight, since the tongue 45 extends up between 30 these members.

In the form of my embodiment shown in Fig. 6, I have made a holder which is somewhat thinner than that shown in the previous figures, since the plate 17 lying between 35 the film sheaths is omitted. In this embodiment, I provide grooves 149 in the side rails 4 separated by V-shaped flanges 150, so that the side flanges 38 may seat themselves against the walls of the groove. In this in- 40 stance, the light-tight joint is formed by the walls of the flange 38 lying against the walls of the groove. Where the plate 17 is omitted, I prefer to form up the ribs 41 and 42 somewhat deeper than is otherwise the 45 case, so that these ribs may contact and form spacing members to hold the plates 43 spaced from each other. These ribs per- 50 form two functions. First, in the manu- facture of the sheaths the ribs are useful 55 in assisting in keeping the bottom 43 of the sheath flat so as to lie in a plane. Second, the ribs form spaced members for holding the sheaths slightly apart, as shown in the embodiment of my invention illustrated in Fig. 6.

With either of the above described em- bodiments of my invention, the holders are comparatively easy to make, since the side and top members of the frame may be as- 60 sembed and a pair of sheaths 15 with or without plate 17 may be thrust into the grooves of the side rails and into the groove of the top, after which the bottom 5' may be placed on the frame to hold the parts in 65 their assembled position. This construc-

tion makes a substantial holder in which the parts are accurately retained in position. The bottom of the sheaths 43 against which the films lie flat are made of a sheet metal preferably reinforced with ribs. Furthermore, the sheaths reinforce each other since they lie back to back, and in the preferred embodiment of my invention the plate 17 also serves to stiffen the film holding part 75 of the holder.

With both forms of my invention light is effectually prevented from leaking from one side through to the other as one film is being exposed. In the first described embodiment flanges 37 and 45 form light lock- 80 ing tongues between the sheaths and in the last described embodiment the V-shaped flanges 150 form the tongues past which light may not penetrate.

Having thus described my invention, what 85 I claim as new and desire to secure by Letters Patent is:

1. In a photographic film holder, the combination with a frame having grooved top and side walls, a tongue on the top wall, a pair of flanged film sheaths carried by their edges engaging in the grooves of the walls, being spaced by the tongue on the top wall, and a stiffening sheet between the sheaths of substantially the same thickness as the 95 spacing tongue of the top wall.

2. In a photographic film holder, the combination with a frame having grooved top and side members, a bottom member having a tongue extending therefrom, of means for 100 holding two films including flanged sheaths, the top and side edges of the sheaths engaging the grooved frame members, and the sheaths lying upon and being spaced apart by the tongue of the bottom member.

3. In a photographic film holder the combination with a frame having top, bottom and side members, of means for supporting film sheets comprising sheaths, and interengaging members on the sheaths and frame 110 members forming a light tight connection between these parts.

4. In a photographic film holder, the combination with a frame having top, bottom and side members, at least two of these members having slots therein, means to hold film comprising a sheath adapted to engage the four frame members and being adapted to lie partially in the slotted members, the depth of the slots being greater than necessary to receive the sheath whereby movement due to expansion or contraction of the frame may be permitted between the sheath in its supporting frame.

5. In a photographic film holder, the combination with a frame, of a pair of film supporting sheaths mounted back to back in the frame, a tongue carried by the frame extending between the sheaths whereby a light tight joint is formed.

6. In a photographic film holder, the combination with a grooved frame, of a pair of film supporting sheaths mounted back to back in the frame, portions of the sheaths being adapted to lie in the grooves of the frame, and tongues extending from portions of the frame between edges of the sheaths to form a light tight joint therebetween. 5
7. In a photographic film holder, the combination with a grooved frame, of film holders adapted to be located in the frame by the grooves, tongues on certain sides of the frame, said tongues being adapted to extend between adjacent edges of the film holders 10 to prevent light from passing therebetween. 15
8. In a photographic film holder, the combination with a frame having top, bottom and side members, of means for holding two film sheaths, each of the sheaths including 20 a flat plate, flanges on edges of the plate adapted to engage edges of a sheet of film to hold the film flat against the flat plate, said sheath flanges also providing frame engaging members by which the two sheaths 25 may be supported with the flat plates placed back to back, by portions of the frame. 30
9. In a photographic film holder, the combination with a frame having top, bottom and side members, of means for holding films therein, including sheaths, each comprising a back formed of a flat sheet of material having flanges around a plurality of sides overhanging the flat sheet, arranged 35
- back to back, a stiffener between the two-sheath backs, the outside edges of the sheaths 40 engaging the inside edges of the frame. 45
10. In a photographic film holder, the combination with a frame, of a film sheath comprising a thin metal plate having a flat base with flanges extending around edges 40 of the base adapted to hold a sheet of film by the edges with the film lying flat upon the flat metal base, means for supporting a sheath in the frame including interengaging parts in the frame and sheath, the interengaging parts being adapted to hold the sheath flat in a fixed plane and to permit slight movement of the sheath in that plane, whereby the sheath may not become distorted due to movement of the frame. 50
11. In a photographic film holder, the combination with a four sided frame, a film sheath comprising a flat base having flanges on edges thereof adapted to engage and hold a film sheet flat thereon, means included between the sheath edges and the frame members for supporting the outside edges of the film sheath on the four sides of the frame, whereby the flat base of the film sheath may be retained in a plane by the 55 frame, said means permitting limited movement of the sheath relative to the frame. 60
